UNITED STATES PATENT OFFICE.

DANIEL M. WATSON, OF PORTLAND, OREGON, ASSIGNOR OF ONE-HALF TO E. A. SESSIONS,
OF PORTLAND, OREGON.

CAR JOURNAL-BEARING.

No. 904,104.

Specification of Letters Patent.

Patented Nov. 17, 1908.

Application filed January 13, 1905. Serial No. 240,961.

To all whom it may concern:

Be it known that I, DANIEL M. WATSON, a citizen of the United States, residing at Portland, in the county of Multnomah and 5 State of Oregon, have invented a new and useful Car Journal-Bearing, of which the following is a specification, reference being had to the accompanying drawing as constituting a part thereof.

10 My invention has for its object to prolong the life in good condition of journal bearings of car axles, and to this end consists of the devices combined with the journals and their bearings, for the purpose of obtaining 15 the features hereinafter fully explained.

In the drawings, Figure 1 shows a longitudinal vertical section of one of the standard or usual axle-bearings of a car, including my improvements; Fig. 2 is a cross section 20 on a line A—A of Fig. 1, but on a smaller scale than the latter, the journal-box however being omitted; Fig. 3 is a perspective of the two middle sections of the sleeve by which the rollers are held in place on the 25 journal; Fig. 4 is a detail on a large scale, showing a part of my improvement; and Fig. 5 is a perspective of one of the rollers.

Referring now to the letters as designating the parts described: The axle-box *a*, the 30 wedge *c*, and the shouldered journal *b* are respectively of the well known type. The bearing *d* is likewise made to answer its usual purpose, except that it does not directly ride or bear on the journal, but merely 35 holds in place the interposed roller-bearing. To this end the bearing *d* is made with a concavity in its inner face in which to receive my roller-bearing devices, and is further made with shoulders *d'* at its ends to 40 engage with the shoulders of the journal of the axle and thereby hold my roller-bearing in place.

My roller-bearing comprises a box-like sleeve *E*, made of a number of sections, *e'*, 45 *e²*, *e³*, *e⁴*, or a greater or lesser number, as deemed convenient. When the sleeve *E* is put together it serves to hold the rollers *j* on the journal, the sleeve *E* being made to fit the said inner face-concavity of the bearing *d*, as shown in Fig. 1, and being made in sections, to facilitate the insertion and arranging of the rollers *j*. I deem it convenient to make the rollers *j* with a peripheral groove *k*, in which to receive a wire *l*,

by which the rollers are loosely tied on the journal. Before arranging and tying the rollers *j* on the journal, the sleeve sections, *e'*, *e²*, should be put in place, and said sleeve sections will then serve to hold the rollers in place, as inserted, and facilitate the tying of 60 the same by the wire. The ends *l'* of the wire *l* are so arranged as to protrude through an opening or cavity *h*, provided therefor on the bottom of the sleeve *E*, as shown in Fig. 1, by cutting away opposite 65 portions *g* from the abutting faces of the two middle sections *e²*, *e³*, thus facilitating the convenient removal of the wire *l* after the parts have been assembled. The cavity *h* also is useful in discharging grit and other 70 matter which may get into the bearing; also to allow lubricant access to the rollers.

The end sections *e'*, *e⁴* of the sleeve *E* are provided with flanges or ring-like retaining means *f*. The latter are represented in the 75 drawings as consisting of removable end-rings, but such construction is a mere matter of convenience to which I do not confine myself.

To prevent the wear of the inner faces of 80 said retaining flanges of the end sections *e'*, *e⁴* of the sleeve *E*, by the ends of the rollers *j*, I make the latter sufficiently shorter to allow the insertion of wear-rings *i*, which could be replaced when worn to any extent, and 85 thereby the bearing maintained in good condition. The wear-rings are preferably split to enable them to accommodate themselves to the inclosing walls of said sleeve sections. Further, I deem it preferable to make the 90 wear-rings with a series of journal holes, and to adapt the ends of the rollers *j* to be journaled in said holes, whereby the rollers are retained in a fixed relation or positioned with respect to each other, the binding or interference of one with the other is prevented, and the working of the bearing as a whole is rendered much better.

I claim:

1. In a journal-bearing, the combination 100 with the axle-journal, of a box-like sleeve surrounding the journal and comprising a plurality of sections the end sections of which are provided with retaining means, wear-rings on the journal against the inner 105 sides of said retaining means of the sleeve and having journal holes, rollers on the journal within the sleeve, the ends of which

rollers are journaled in said wear-rings, and a bearing seated on said sleeve and arranged to hold the same in place on the axle-journal.

2. A journal bearing comprising a shou-
5 dered axle-journal, a box-like sleeve, sur-
rounding the journal, and comprising a plu-
rality of sections, the end-sections of which
are provided with retaining means, and the
middle two sections having portions of the
10 opposed faces cut away, at the bottom, for
the purpose described, wear - rings on the
journal against the inner sides of said retain-
ing means of the sleeve and having journal-
holes, rollers on the journal within the sleeve,
15 the ends of which rollers are journaled in
said wear-rings, and a bearing seated on said
sleeve and arranged to hold the latter in
place between the shoulders of the axle-
journal.
- 20 3. In a journal bearing, the combination
with an axle-journal, of a box-like sleeve

surrounding the journal and comprising a plurality of sections, the end sections of which are provided with retaining means, and the middle two sections having portions 25 of the opposed faces cut away at the bottom, for the purpose described, wear-rings on the journal against the inner sides of said retaining means of the sleeves, and having journal-holes, rollers on the journal within the sleeve, 30 the ends of which rollers are journaled in said wear-rings, and a bearing seated on said sleeve and arranged to hold the latter in place on the axle-journal.

In testimony whereof, I have hereunto af-
fixed my signature in the presence of two 35
witnesses, this 10th day of October, 1904.

DANIEL M. WATSON.
